UNITED STATES PATENT OFFICE.

HERBERT W. DERRICK, OF BOSTON, MASSACHUSETTS.

EYEGLASSES.

No. 884,368.

Specification of Letters Patent.

Patented April 14, 1908.

Application filed January 10, 1908. Serial No. 410,073.

To all whom it may concern:

Be it known that I, HERBERT W. DERRICK, a citizen of the United States, and resident of Boston, in the county of Suffolk and State 5 of Massachusetts, have invented an Improvement in Eyeglasses, of which the following description, in connection with the accompanying drawings, is a specification, like letters on the drawings representing like 10 parts.

My invention relates to that class of eye glasses in which the opposite lenses are held together by a yielding connection or spring bridge, the latter receiving its main yielding 15 or springing action by the formation at its opposite ends.

The principal objects of my invention are to secure extra spring or yield in a horizontal plane, provide balanced movement and rigidity and steadiness against improper twisting or movement. To this end, I provide a 20 double horizontal loop or coil which straddles or embraces the bridge or nose-spring at each end of the latter, said two loops preferably 25 terminating in two arms clamped into the holding groove of a usual lens stud, thereby rendering it practically impossible for the parts to work loose. The double loops, *i. e.* two loops extending in a horizontal plane, 30 one located above the bridge and the other below the bridge, give great steadiness and prevent the lenses from moving in any but a horizontal plane. Also, the two arms, one 35 on each side of the holding screw, give rigidity and aid materially in holding the nose guard flat and steady.

Further advantages, and the constructional details of various selected embodiments of my invention will appear more fully 40 in the course of the following description, taken with reference to the accompanying drawings.

In the drawings, Figures 1 and 2 show respectively in front elevation and top plan 45 one embodiment of the invention; Figs. 3, 4, and 5 are sectional views showing in end elevation the constructional details of three embodiments of the invention, the nose guard in each instance being shown as detached in 50 order to reveal the further constructional details of the main part of the invention; Fig. 6 is a view similar to Fig. 2 of another form of the invention; and Fig. 7 is an enlarged perspective view of one form of the double loop.

55 The general construction of the eye glass may be of any usual or preferred kind, being

herein shown as comprising two rimless lenses 1, each provided with a fastening stud 2 secured by usual screws 3. As shown in Figs. 1-4, the fastening studs have a vertically grooved head 4, whereas in Figs. 5 and 6 the stud is provided with a horizontal or transversely grooved head 5. The bridge or nose spring 6 may be of any shape and kind desired, preferably having more or less spring 60 itself, although my invention resides in providing extra spring or yielding capacity at the ends of this bridge. For this purpose I provide two loops or horizontal coils 7, 8 extending from the end of the bridge at 9, and thence curving around horizontally and diverging sufficiently to permit the coil 7 to pass over the bridge and the coil 8 to pass under said bridge. In other words, the two coils come together at one end, and constitute, 70 or are permanently connected to, the end of the bridge, and they diverge slightly at their other end and straddle or embrace the same ends of the bridge. The opposite ends of the bridge are bent in a horizontal curve, forwardly and thence toward each other, and thence rearwardly transversely of and embracing the body of the bridge, and the slots provided for the passage of the body of the bridge between the two coils constitute guiding 80 means for compelling the normal yielding action to be horizontal. These two coils in Figs. 1, 2, 3, and 7 have their free ends 10, 11 bent parallel and extended downwardly at the opposite sides of the box or stud head 4 85 in position to be clamped by a set screw 12 and an adjacent portion of a nose guard 13, thereby providing an exceedingly strong, 90 rigid, immovable joint.

In Fig. 4 the free ends of the two coils 7, 8 95 are bent farther apart at 14, 15 than in the form of my invention shown in Figs. 1-3, and are thence bent parallel to each other, but in opposite directions, as clearly shown at 16, 17 in said Fig. 4, being secured in substantially the same manner by a nose guard 18, and in Figs. 5 and 6 the two coils 7 and 8 have their free ends 19, 20 extended parallel 100 in a straight rearward direction to the position best shown in Fig. 5, where they are clamped in the stud head 5 by suitable means in substantially the same manner as previously. While I prefer that the two coils shall be made integrally with each other, this construction is not necessary in all cases, and 105 in Fig. 6 I have shown the bridge as composed of two wires twisted together, one of

which forms the upper loop and the other the lower loop, the construction otherwise being the same as in Fig. 5. In the construction shown in Figs. 1-3, the loops are located above the box or stud, whereas in the construction of Figs. 4-6 they are located in front of the stud, and hence produce a somewhat neater effect, although I wish it understood that the particular location of the loops may be varied, and I do not limit the loops to being located either above or below, or at the front or at the rear of the studs, but for some purposes I prefer the construction shown in Fig. 4, which is exceedingly compact, strong, and neat.

The double loop at the end of the spring or bridge is not only more resilient, but it makes the glasses more durable. The two arms secured in the box or head of the stud, one at one side and the other at the other side of the box, being fastened by the small screw stud and the adjacent portion of the nose guard, not only aid in holding the guard flat, but give great rigidity and steadiness of movement to the adjacent lens, one spring end pressing against the other spring end so as to prevent to a large degree twisting and improper movements, thereby restricting the main yielding movement to a simple back and forth horizontal bending at the bridge. Notwithstanding the fact that my invention provides greater flexibility than the usual construction, and gives extra spring at the ends of the bridge, I accomplish this without introducing any uncertainty of yielding action, and, in fact, my invention restricts the movement almost entirely to a horizontal plane.

As already stated, I do not intend to restrict my invention to the particular arrangement and formation of parts herein shown, as it is capable of a wide variety of embodiments without departing from the spirit and scope of the invention as set forth in the following claims.

Having described my invention, what I claim as new, and desire to secure by Letters Patent, is:

1. In an eye glass, a lens, a stud, and a bridge, the latter being connected to said stud by two spring loops extending horizontally approximately parallel, and branching independently from the bridge at one end, and each loop having its own opposite end connected to the stud.

2. In an eye glass, a lens, a stud, a bridge, and two loops forming two connecting means between the stud and adjacent end of the

bridge, each loop having two ends, the adjacent two ends, one of each loop, being connected directly to the bridge, and the other two ends, one of each loop, being connected to said stud.

3. In an eye glass, a lens, a stud, and a bridge, the latter being connected to said stud by two spring loops extending horizontally approximately parallel, one of said loops passing transversely above the adjacent end of the bridge and thence to the stud, and the other of said loops passing transversely beneath the adjacent end of the bridge and thence to the stud.

4. In an eye glass, a lens, a stud, and a bridge, the latter being connected to said stud by two spring loops extending horizontally approximately parallel, one of said loops passing transversely above the adjacent end of the bridge and thence to the stud, and the other of said loops passing transversely beneath the adjacent end of the bridge and thence to the stud, the free ends of said two loops being arranged parallel to each other on the head of the stud, and securing means for clamping said free ends in said position.

5. In an eye glass, a lens, a stud, and a bridge, the latter being connected to said stud by two spring loops extending horizontally approximately parallel, one of said loops passing transversely above the adjacent end of the bridge and thence to the stud, and the other of said loops passing transversely beneath the adjacent end of the bridge and thence to the stud, the free ends of said two loops extending substantially parallel in opposite directions, and entering the head of the stud from opposite directions, and securing means for clamping said free ends in said position.

6. In an eye glass, opposite lenses, and fastening studs, combined with a bridge or nose spring having its opposite ends bent in a horizontal curve forwardly and thence toward each other and thence rearwardly transversely of and embracing the body of the bridge, each end being provided with a guiding slot to permit the bridge to yield horizontally with relation to the free end of said curved portion, the latter being secured to the adjacent stud.

In testimony whereof, I have signed my name to this specification, in the presence of two subscribing witnesses.

HERBERT W. DERRICK.
